(54) **THRASHING MACHINE**

(76) Inventor: **Joseph Tyler**

Joseph Tyler, of Brooklyn, State of Connecticut.

Letters Patent.

The schedule referred to in these Letters Patent and making part of the same containing a description in the words of the said Joseph Tyler himself of his improvement in, ^{the mode of} making Machines for thrashing all kinds of grain called Tyler Improvement in Thrashing.

To all to whom these presents shall come,

Joseph Tyler of Brooklyn in the County of Kings and State of Connecticut Gentleman sends greeting,

Be it known that the said Joseph Tyler, have invented, made, and applied to use, a new and usefull improvement in Thrashing grain called Tyler Improvement in Thrashing Specified in the words following, viz; Specification in Tyler Improvement in Thrashing. The machine is placed in a frame, which can be removed at pleasure. Description of the frame, and directions in what manner to build the same. The frame is built of 14 posts 4 feet high made of solid timber 3 inches by 11 inches, with four caps on the top, framed together and also framed and connected to the said posts by tenons and mortises passing into the caps, one crop girt framed into the two end posts under the apon so that the apon may rest on it 22 inches from the bottom of the post, One crop girt is also framed into the other end posts, the same height as the former, both made of square timber half the size of the post, 2 girts or side bearings running lengthwise of the frame made of timber 2 $\frac{1}{2}$ inches square, falling half their width below the crop girts. These side bearings are let into the posts half an inch and secured at each end to the post, by an iron bolt headed at its inner end and screw and nut at the outer end, running through the post. These side bearings sustain the main asber, at each end thereof.

The frame is lined on the inside with boards 26 inches thick, made fast to the inner side of the frame so that the cylinder runs within said lining boards. Description of the machine. The main asber is made ~~and~~ of wrought iron 1 $\frac{1}{2}$ inch diameter either round or square and passes through

The center of the cylinder extending over and resting upon the side bearing. The cylinder is 18 inches long, and 18 inches in diameter and made in the usual and common form of cylinders for the present threshing machine, with 5 iron lugs at equal distances apart from end to end, in each lug there is two rows of iron beaters, riveted and countercrunk, into the lugs, these beaters are three inches long, the lugs are secured to the cylinder by iron hoops at each end with rivets through them. Below the cylinder rest the under curve corresponding with the cylinder in form, into which the cylinder moves. In this under curve is fixed two double rows, and one single row of iron beaters, the same size and length of the beaters as the lugs, all of which are made of iron 3 inches long, and 5 in each row, and so arranged that those on the cylinder overlap between those in the under curve. The under curve extends from the abpon to the center of the cylinders and one inch beyond it. The super curve covers the upper side of the cylinder in the same manner, as the under curve does the under side of the cylinder, and opposite to it, leaving on the front side, an aperture for the entrance of the unthreshed grain, and on the other side an aperture for the straw and the threshed grain, as they escape from the machine.

On each side bearing is made fast on the top of it, a rising box composed of cast iron for the friction roller, rising above the side bearing so as to permit the friction roller to revolve above the top of the side bearing. Upon each of these rising boxes rests a pair of friction rollers, 3 inches diameter, made of cast iron finished in the lathe with a short arbor running through each, resting on said boxes, and upon the top of these friction rollers rests the ends of the main arbor, so that the revolutions of the main arbor, also cause these friction rollers to revolve upon their axes. On the end of the main arbor is a fixed position, is the cast iron pinion wheel 2 1/2 inches diameter with 19 or more cogs in the edge thereof at equal distance.

The Driver wheel has its central position over the pinion wheel, 20 inches in diameter, made with arms and a rim, all of cast iron. The rim 3/4 inch thick upon the outer edge of which is cut cogs to operate with the cogs on the pinion wheel. Through the center of the Driver wheel passing an iron arbor, 1 inch diameter resting on the friction wheel, made for the same, which run in boxes and sustain this arbor, in the same

manner as those above described, for the arbor of the cylinder and to the end of this arbor is fixed the turning crank, with its handle composed of iron.

The arbor of the Driver wheel is secured by two iron clamps, passing over the arbor and made fast at each end by screws. The upper bearing is 3 inches through 2 inches thick secured to the post by iron bolts at each end, with a nut and screw with a long mortise in the same, up and down of sufficient width for the Driver wheel to revolve, while the arbor of the arbor wheel rests on each side of said mortise that being the position of the friction rollers for said Driver wheel.

The balance wheels are made of cast iron weighing about 75 pounds each, one of which is placed on the main arbor of each end of the cylinder, having the lining board between the cylinder and the balance wheel - these balance wheels are made with a rim and arm 24 inches diameter, and so secured to the main arbor that the balance wheel, revolves with the cylinder.

The apron is 20 inches wide, and 3 inches deep receiving the untrashed grain, and conducts it to the beaters. The whole machine is propelled by hand power, and may be operated by one man, while the grain is fed by another or by any other power not exceeding the power of one man. The machine may stand on any floor, and removed at pleasure.

The several parts of said frame and machine, may be increased or diminished, from the above dimensions, preserving the same proportions.

The present claimant does not seek a patent for the cylinder, for the beaters, for the arbors, nor for the undercurve, because these parts of the said machine have long been in use, and are no invention of the present claimant, but he does claim that the pinion wheel, balance wheels, friction rollers, their size and proportions, and the mode of their application to this machine are entirely new, and are of the original invention of the present claimant, and also this claimant further claims as his invention the great reduction of power necessary to propel this machine and the great diminution of friction, which has heretofore retarded in a great measure the operation of machines of this description.

For testimony that the above is a true specification of my said improvement as above described I have this day set my hand the 1st day of April in the year of our Lord

United States Patent

Patent No.: X8961
